UNITED STATES PATENT OFFICE.

EMIL JAGENBERG, OF DUSSELDORF, GERMANY.

BOX-MAKING MACHINE.

1,100,740.

Specification of Letters Patent. Patented June 23, 1914.

Application filed October 18, 1913. Serial No. 795,833.

To all whom it may concern:

Be it known that I, EMIL JAGENBERG, manufacturer, a subject of the German Emperor, and residing at 107 Himmelgeisterstrasse, Dusseldorf, Germany, have invented certain new and useful Improvements in Box-Making Machines, of which the following is a specification.

Boxes made on the machine described in the United States Letters Patent No. 1,016,266 or by other means have the disadvantage, that the edges at the open side have a slightly outward curve owing to the stiffness of the pasteboard employed. When, therefore, the two halves of the box are assembled, the joint will not be perfectly tight. In order to remedy this evil these edges of the boxes are bent inwardly according to the present invention, before the boxes are ejected from the box making machine, so that when the elasticity of the pasteboard makes them recede, they will go back only so far that they form a straight line.

The present invention is exemplified in an embodiment in a box making machine of the kind disclosed in the United States Letters Patent No. 1,016,269.

Figure 1 is a cross section through the machine and shows the matrix slide in elevation. Fig. 2 is a longitudinal section through the machine. Fig. 3 is a plan of the respective part of the machine. Fig. 4 is a view similar to that in Fig. 1, showing the machine in a different operative position. Fig. 5 is a cross section through the matrix.

As described in the United States specification 1,016,269 the box contained in the matrix 39 and wrapped in the strip of paper is displaced to the side by the operation of the slide 29 to which the matrix is fitted, by means of lever 36, which is rocked by the cam disk 37. As there described the folders 30^a and 31^a are moved by means of the stops 72 and 73 after each other in front of the edges of the box, so that the projecting parts of the wrapping strip are folded over inward. When the slide 29 with the matrix 39 has reached its terminal position, the folders have receded again outward. At this position the matrix 39 is situated in front of the plunger 75 which is then pushed into the box in known manner by means of the cam disk 77 and thereby folds over inward the projecting parts of the wrapping

paper and presses it tightly against the inside of the box. Opposite to this plunger 75 is a slide 38 displaceable in guide 40 on the body of the machine. This slide carries at its front end a plate 41 which can enter through an opening 42 in the guide of slide 29 behind the matrix in its terminal position. The slide 38 is coupled to the bell crank 43 pivoted to the body of the machine, the other arm of which is coupled to a rod 44 by means of pin 49, to the free end of which rod is hinged a fork 45 by means of a pin 46, which engages around shaft 36. The fork carries a roller 47 which bears against a cam disk 48 on shaft 36^a. By the rotation of the shaft 36^a the plate 41 is then moved forward and back.

When the plunger has been pushed into the box toward its end the plate 41 settles against the outside of the bottom of the box so that the latter is seized between the plunger 75 and the plate 41. The plunger 75 then recedes and at the same time and at the same rate the plate 41 advances so that the box held between them is pushed out of the matrix. When the box has emerged by about one half from the matrix the plunger 75 and the plate 41 come to a standstill and hold the box in this position.

To the slide 29 is fitted a rail 50. This rail passes through an eye 51 in the arm 52 carrying the one folder 31^a and is displaceably held to the slide 29 by means of the plate 53. In the rail 50 is provided a slot 54 in which a pin 55 on the one folder arm 30^a engages. When the slide 29 has reached the above described terminal position, the end of the rail 50 bears against a lever 56 which is fitted to a shaft 57, journaled in the body of the machine. This shaft also carries a lever 58, to the end of which a roller 59 is rotatably fitted, which rides in a groove in the cam disk 60. The cam disk is fitted on the shaft 61 also carrying the cam disk 77, so that by its rotation also the lever 56 is oscillated.

When now the box has been ejected by one half from the matrix, the lever 56 moves toward the rod 50 so that the latter is advanced. A shoulder 62 on the latter then bears against the arm 52. In consequence thereof the folder arms 31^a are moved by this shoulder and the folder arms 30^a by the pin 55 toward inside so that they bear against the side walls of the box. The folders 30 and 31 on the folder arms 30^a and 31^a

respectively are curved on their operative edge. The sides of the box are thereby bent inward as shown in Fig. 4. Then the lever 56 recedes and the folders are again swung outward by the springs 30^b and 31^b. The sides of the box will then, in consequence of the elasticity of the paste-board yield partly again, but only so far that their edges form a straight line. Now the plunger 75 recedes alone. Then the plate 41 advances and completely ejects the box from the matrix, so that it falls into the inclined chute 63 and slides down the same into a collecting box.

I claim:

15. A box making machine comprising a slide, adapted to assume two consecutive po-

sitions, a wrapped box blank holding matrix carried thereby, a plurality of arms having folders, and displaceable along with the slide, means for turning said arms inwardly at the first slide position, a plunger for partly ejecting the box blank from the matrix, during the second slide position, and additional means for turning said arms inwardly during said second slide position.

In testimony whereof I have hereunto set my signature in the presence of two witnesses.

EMIL JAGENBERG.
